CLAIM

The ornamental design for a repellent strip, as shown and described.

DESCRIPTION

FIG. 1 is an axon view of a repellent strip showing my new design;

FIG. 2 is a front view of the repellent strip shown in FIG. 1; FIG. 3 is a first side view of the repellent strip shown in FIG. 1; and,

FIG. 4 is a second side view of the repellent strip shown in FIG. 1.

The rear of the repellent strip is plain and unornamented.
